CONVEYER FOR BOTTLE WASHERS

Frank L. Darling, Baltimore, Md., assignor to
 Anchor Cap & Closure Corporation, Long Island
 City, N. Y., a corporation of New York

Application December 11, 1931, Serial No. 580,441

2 Claims. (Cl. 198—33)

The present invention relates to method and means for cleansing filled and sealed containers, of the type provided with a top opening sealed by a closure cap having a depending skirt whose lower inner marginal portion is spaced at least in part from an embraced container portion, so that foreign matter may be effectively removed from the space existing between the marginal portion of the closure skirt and embraced container portion.

According to the invention, the sealed container is passed along a prescribed path and fine streams of water are directed upwardly between the skirt of the closure and the embraced portion 15 of the container. Through suitable means, of which a novel exemplification will be described, relative rotation is effected between the container and the streams of water so that the latter are impinged against the full circumferential extent 20 of the former. As a result of the cleansing action, foreign matter or accumulations due to careless filling, are washed out from under the cap and are removed by the falling film of water which envelopes the container. Consequently, sticking 25 of the cap due to hardened accumulations and rust caused by the action of acids, brine or vinegar are prevented and a clean appearance is presented when the closure is removed.

In the accompanying drawings:

30. Figure 1 is a side elevation, partly in section, of apparatus for carrying out the present invention.

Figure 2 is a plan view, partly in section, of the apparatus shown in Figure 1.

Figure 3 is a section on the line 3—3 of Figure 35 2, and

Figure 4 is a fragmentary section of a container and spraying means.

Referring to the drawings, reference numerals 5 and 6 designate vertically adjustable pedestals 40 which at their upper ends support a substantially horizontal I-beam 7, the latter being disposed with its flanges in substantially vertical planes and with the connecting web 8 in a horizontal plane and provided with perforations as at 8', 45 Figure 3. Adjacent pedestal 5 is revolvably mounted a foot sprocket 9, the plane of the sprocket being in the longitudinal central line of the I-beam 7. Adjacent the pedestal 6 is mounted a drive sprocket 10, an endless chain 11 being trained over the two sprockets and carrying flat horizontal plates 12 whose lower outer edges on the upper run of the chain slightly overlie the I-beam flanges, Figure 3, to be guided thereby as a substantially continuous flat supporting means 55 for the containers to be washed. Yokes 13 and

14 secured to the beam 7 support a guide plate 15 for the lower run of chain 11.

On a shelf 16 supported by means of a stirrup 17 on pedestal 6 and a strap 18 depending from the beam 7 is mounted a motor 19 which through a speed reduction unit 20 supported on the shelf drives a sprocket 21 which engages a chain 22 to drive a sprocket 23 fixed on a shaft 10' to which the sprocket 10 is fixed. The motor serves to drive chain 11 so that the top run travels from left to right, Figures 1 and 2, at proper speed.

Referring to Figure 3, a strip 24 with its top surface somewhat higher than the plate 12 is fixed in longitudinally extending relation to the upper run of the chain and adjacent the right hand edges of the plates 12, Figure 3. The top of strip 24 is preferably knurled, assuming the strip to be of metal, and constitutes a ledge on which one side of a sealed container 25, to be washed, is supported. The purpose of strip 24 is to exert a drag on one side of the container so that the container resting at a diametrically opposite point on the plates 12 will be rotated by the latter. If desired, strip 24 may be of rubber or other similar friction material.

Posts 26 and 27 are secured to the flanges of rail 7. Posts 27 support a guide strip 28 directly above strip 24, strip 28 through screw and slot connections supporting uprights 29 which at their upper ends carry a horizontally extending pipe 30 provided with inwardly and upwardly directed perforations 30'. Posts 26 are provided with transverse bores in which are supported pins 31 adjustably retained by means of cap screws 32 threaded in counter bores of the posts. Pins 31 support a guide strip 33 upon which are mounted for vertical adjustment through screw and slot connections, uprights 34 which support a pipe 35 provided with inwardly and upwardly directed perforations 35'.

Container 25 is here shown as a jar provided with a cap 36 having a crimped depending skirt 37 embracing a top bead 25' of the jar and as is clearly shown in Figure 4, spaces as at 38 exist between the lower edge of the skirt and the underlying portion of the jar, these spaces being apt to become packed with foreign matter during sealing or subsequent handling.

In the operation of the machine above described, guide strip 33 is adjusted in accordance with the diameter of the container and uprights 29 and 34 are adjusted in accordance with the height and form of the container so that streams will be directed through openings 30' and 35' between the skirt 37 and bead 25', water be-

ing admitted to pipes 30 and 35 through a connection 39. The containers are placed in a tray 40 and fed between strips 28 and 33, whereupon they are carried throughout the extent of the 5 latter and continuously rotated through the provisions above described, the streams of water continuously impinging the containers under the caps to clean out the spaces 38 and the water running down the sides of the containers to carry 10 off any foreign matter washed out. A baffle 41 at the head end of the conveyer serves to deflect the containers from the conveyer to a tray 42 whence they may be removed as desired.

A trough 43 secured at its upper edges to beam 15 7 catches the wash water and delivers it to an outlet 44. A hood 45 supported on the upper edges of trough 43 encloses the path of travel of the containers.

While I have shown a container in the form 20 of a jar, it will be understood that the present invention is concerned with containers of all types utilizing a skirted closure cap. It will be evident that if the containers to be cleansed are bottles, uprights 29 and 34 must be shaped accordingly, 25 so that pipes 30 and 35 will be supported in proper position to direct streams of water underneath the closure caps. I have, of course, used the word "water" as a general term intended to cover any suitable cleansing fluid, or vapor, such as 30 steam.

While I have described a particular form of apparatus for carrying out my invention, it will be understood that I do not limit myself under the present invention except as determined in the following claims.

80

I claim:

1. In apparatus of the class described, a horizontally extending conveyer having a top substantially flat supporting surface, a fixed ledge extending alongside said supporting surface and having a top horizontal portion above said supporting surface, and means for guiding a circular upright container for transport longitudinally of the conveyer with its bottom partially on said supporting surface and partially on the top horizontal portion of said ledge whereby the container is rotated during its travel.

90

2. In apparatus of the class described, a horizontally extending conveyer having a top substantially flat supporting surface, a fixed ledge extending alongside said supporting surface and having a top horizontal portion above said supporting surface, and a guide strip opposite the ledge for guiding a circular upright container for transport longitudinally of the conveyer with its bottom partially on said supporting surface and partially on the top horizontal portion of said ledge whereby the container is rotated during its travel.
